UNITED STATES PATENT OFFICE

161,405

FISH GRIP

Charles J. Achenbach, Manitowoc, Wis.

Application May 4, 1950, Serial No. 9,694

Term of patent 14 years

(Cl. D44—4)

To all whom it may concern:

Be it known that I, Charles J. Achenbach, a citizen of the United States and resident of Manitowoc, in the county of Manitowoc and State of Wisconsin, have invented a new, original, and ornamental Design for a Fish Grip, of which the following is a specification, reference being had to the accompanying drawing, forming part hereof.

Figure 1 is a side elevational view of my fish grip, showing my new design.

Figure 2 is a top plan view thereof.

Figure 3 is a rear end elevational view of the fish grip, and

Figure 4 is a front elevational view of the fish grip.

I claim:

The ornamental design for a fish grip, as shown.
CHARLES J. ACHENBACH.
